TIRE

James F. Newman, St. Clair Shores, Mich., assignor to

Uniroyal, Inc., a corporation of New Jersey
Filed Oct. 4, 1966, Ser. No. 4,159

Term of patent 14 years

(Cl. D90—20)

FIG. 1 is a perspective view of a tire embodying my new design, it being understood that the full-line portion is repeated throughout the circumference of the tire, shown by means of broken lines;

FIG. 2 is an enlarged, fragmentary, elevational view of the full-line portion shown in FIG. 1;

FIG. 3 is an enlarged, fragmentary, plan view of the full-line portion shown in FIG. 1; and

FIG. 4 is a fragmentary sectional view taken substantially on the plane indicated by the line 4-4 in FIG. 2.

The dominant features of my design reside in those portions shown in full lines in the drawings.

I claim:

The ornamental design for a tire, substantially as shown and described.
